UNITED STATES PATENT OFFICE.

GEORGE M. RAMAGE, OF SNYDER, TEXAS.

AUTOMATIC CULTIVATOR-TOOTH-RELEASING MEANS.

Application filed May 20, 1924. Serial No. 714,622.

To all whom it may concern:

Be it known that I, GEORGE M. RAMAGE, a citizen of the United States, residing at Snyder, in the county of Scurry and State 5 of Texas, have invented certain new and useful Improvements in Automatic Cultivator-Tooth-Releasing Means, of which the following is a specification.

This invention relates to new and useful 10 improvements in planter attachments and has for its principal object to provide a means for automatically releasing the cultivator tooth when the same encounters an obstruction, thereby preventing the breaking 15 of the tooth and automatically returning the same to its normal position after the planter has passed over the obstruction.

A further object of the invention is to provide a planter attachment of the above 20 mentioned character, wherein the cultivator beam is adjustably supported on the foot of the planter, so as to regulate the depth at which the tooth is to operate.

A further object is to provide a device of 25 the above mentioned character, which is simple in construction, inexpensive, strong and durable, and furthermore adapted for the purposes for which it is designated.

Other objects and advantages of this invention will become apparent during the 30 course of the following description.

In the accompanying drawing, forming part of this specification, and in which like numerals designate like parts throughout 35 the same:

Figure 1 is a side elevation of the elements embodying the invention, and

Figure 2 is a top plan view thereof.

In the drawing, wherein for the purpose 40 of illustration is shown the preferred embodiment of my invention, the numeral 1 designates the foot of a planter and secured thereto on opposite sides thereof are the brackets 2 and 3 respectively. The brackets 45 extend rearwardly from the foot 1 and the rearwardly extending portions are provided with registering apertures such as are shown at 4 in the drawing. The rearwardly extending portions of the brackets are furthermore provided with registering elongated slots such as shown at 5, and the purpose of this construction will be presently described.

Disposed between the brackets 2 and 3 is 50 the inner end of the plow or cultivator beam 6. The inner end of the beam is pivotally

supported at 7 and the pivot is adapted to extend through one pair of registering openings 4 provided in the rearwardly extending portion of the brackets.

Extending through the registering slots provided in the bracket is the bolt 8 and a suitable washer 9 is carried thereon and adapted to engage the corrugations 10 provided on the outer face of the rearwardly 60 extending portion of the bracket 3, it being understood that the inner face of the washer is also corrugated, to cooperate with the corrugations 10. A nut 11 is threaded on the bolt 8 and the bolt is disposed below 65 the under side of the beam for supporting the same in the proper adjusted positions with respect to the brackets in the manner as is obvious from the construction shown in Figure 1.

Pivotedly supported at 12 on the lower end of the beam 6 is the cultivator tooth carrying shank 13. The shank is provided on its upper end with the extension 14 which fits around the lower end of the beam 80 and is adapted to engage the stop member 15 carried by the lower end of the beam. The cultivator tooth 16 is fastened to the shank 13 by any suitable fastening means, such as shown at 17.

For normally holding the tooth 16 in an operative position when the planter is in use, I provide the coil spring 18, one end of which is connected to the foot 1 in the manner shown at 19, while the opposite end is 85 fastened to the eye portion 20 of a bolt 21 which extends through the shank 13 and receives on its threaded end the adjusting nut 14' whereby the tension of the spring may be regulated as is desired.

Normally, the parts are arranged as shown in Figure 1 of the drawings, and as the planter moves along the ground, the tooth 16 will work in the soil for the purposes for which it is designated. Should 100 the tooth accidentally encounter a stump or any other obstruction, the tooth will automatically swing on its pivot 12 against the tension of the coil spring 18 whereby the planter on its forward movement will 105 be caused to move the tooth over the obstruction in such a manner as to prevent the breaking off of the tooth and after the tooth has passed the obstruction, the coil spring 18 will return the same to its normal position. The extension 14 will then engage 110 the stop 15 and limit the forward swinging

movement of the tooth and the shank upon which the same is mounted.

It will thus be seen from the foregoing description, that an automatic release for a 5 cultivator tooth has been provided which is simple in construction, strong and durable and further will positively enable the tooth to be returned to its normal operative position after the same has passed the obstruction which it has encountered. In this 10 manner considerable expense will be saved by obviating the necessity of having to purchase new plow teeth and the nut 14 enables the tension of the coil spring 18 to be 15 regulated so as to assure the proper operation thereof in returning the cultivator tooth to its normal operative position.

While I have shown the preferred embodiment of my invention, it is to be understood that various changes in the size, shape 20 and arrangement of parts may be resorted to, without departing from the spirit of the invention and the scope of the appended claims.

25 Having thus described my invention, what I claim is:

1. In combination, a plow foot, a bracket secured thereto and extending rearwardly therefrom, said bracket including spaced 30 plates arranged on opposite sides of the

foot, means for pivotally and adjustably securing the inner end of a plow beam between said plates of said bracket, a plow tooth pivotally supported on the lower end of the beam, a coil spring secured at one end to the plow foot and to the tooth at its opposite end, means for regulating the tension of said spring, and means for limiting the movement of the tooth in one direction. 35

2. In combination, a plow foot, a bracket secured thereto and extending rearwardly therefrom, said bracket including spaced plates arranged on opposite sides of the foot, means for pivotally and adjustably 40 securing the inner end of a plow beam between said plates of said bracket, and a plow tooth pivotally supported on the lower end of the beam; a coil spring secured at one end to the plow foot and to the tooth at its opposite end, means for regulating the tension of said spring, means for limiting the movement of the tooth in one direction, 45 said means comprising an extension formed on the upper end of the tooth carrying members and adapted for engagement with a stop provided on the lower end of the beam.

In testimony whereof I affix my signature.

GEORGE M. RAMAGE.
